VARIABLE DELIVERY PUMP OR MOTOR

Elek K. Benedek, Bucyrus, Ohio

Application December 31, 1935, Serial No. 56,954

2 Claims. (Cl. 103—161)

This invention relates to variable delivery pumps or motors of the radial piston type in which the piston actuating reactance ring is in floating driven relationship with respect to the 5 rotating pistons and cylinders.

In the type of pumps hereinabove referred to the pistons are actuated by cross pins engaged at each side of the piston head in a floating reactance support. In such piston actuating assembly under high hydraulic radial piston load and during the pressure cycle of the piston and cylinder assembly respectively, the piston cross head will yield elastically in the direction of load permitting the fluid medium to expand slightly until 10 new equilibrium is reached between the elastic cross pin and the elastic pressure fluid. In such instances it is obvious that the plurality of radial pistons when rotating at substantially high speeds and making during each revolution a pressure 15 stroke and a suction stroke, respectively, the elastic deflection of the cross pins will cause an elastic impulse to the elastic fluid confined between the pressure pistons and the pressure port of the pintle. Assuming for the purpose of illustration, 20 a pump working under 3000 pounds per square inch operating pressure with 7 pistons and at 900 R. P. M. It will be obvious that during each revolution 7 elastic impulses will be transmitted to the resultant flow of the pump delivery effected 25 by 3 or 4 pressure pistons respectively, which will be imparted to the pressure port of the pump. At 900 R. P. M. it is obvious that the working fluid will receive about 15 periodic impulses due to cross head deflections and subsequent expansion of the 30 pressure fluid in each second, which results in substantial noise and vibration.

One object of this invention is to provide for the pumps hereinabove referred to a piston actuating reactance ring, which will support the hydraulic piston load directly, in the zone of the working reaction and thus to eliminate noise and vibration by eliminating the deflection of the 35 cross pins.

A further object is to combine a radial reciprocating piston actuating head with a central radial flange provided in the zone of the pistons and working reactance respectively and with a piston actuating cross pin respectively, in such a manner that a floating reactance ring will support said cross pin directly in the zone of the working reaction and throughout the entire length of the pin.

A further object is to provide a self aligning floating connection between the outer ends of the pistons and said radial enlarged piston actuating heads.

A further object is to provide secondary piston actuating means snugly arranged at each side of the guide flange of the cylinder barrel and the associated piston head for the purpose of actuating the cross pins during suction periods of the 5 piston only.

A further object is to provide anti-friction connection between said secondary piston actuating means and the head actuating cross pins in a novel manner.

A further object is to provide a novel bearing structure or support which will engage directly 10 the head actuating cross pins or primary thrust means and the axially spaced cross pin actuating secondary rings respectively.

A further object is to provide a rigid bearing structure for the rotary support of the floating piston actuating reactance.

Further objects and advantages will be described in connection with the drawings forming 20 a part of the following specifications.

In the drawings:—

Fig. 1 is a central longitudinal sectional view of the pump disclosed for the purpose of illustration, certain parts being shown in elevation.

Fig. 2 is a transverse sectional view taken on line 2—2 in Fig. 1, showing the rollers of the reactance bearing support as well as certain pistons in elevation instead of in section.

Fig. 3 is an axial sectional view of a modified 30 form of rolling thrust pin.

Fig. 4 is a cross sectional view of the pin illustrated in Fig. 3.

The pump disclosed for illustration comprises a central cylindrical valve 1, having a rigid support in the casing 38. The supported portion of the pintle as at 1 is pressed in the casing, in order to obtain for the active pintle portion 2 an accurate position for the pintle in assembly. The stationary member 36 of the reactance support 32 is guided in a cylindrical portion of the casing 38, not shown in the drawings. It is imperative to mount the pintle 2 absolutely concentric with the cylindrical portion of the casing for the reason of supporting and confining the reactance 45 support 32 and the reactance stator 36 respectively to parallel positions in every adjusted relative position between the pintle and reactance. To obtain such accurate assembly I finish machine the internal face of the radial wall of the 50 casing, as at 38a, as well as at 38b to provide accurate supporting surfaces for the casing, and bore a hole in the center of the radial wall for the large portion of the pintle 1. In order to obtain a rigid as well as hydraulically sealed connection 55

for the external ports 5 and 6 respectively, of the pintle, I finish the bore 38c for the pintle in the hub portion of the case 38 to a dimension slightly smaller than the diameter of the large 5 pintle portion 1. In order to eliminate the tipping of the pintle in bore 38c of the casing, I propose to use a novel method of assembly which will eliminate expensive fixtures for the conventional pressing in operation used heretofore. It 10 will be noted that at the beginning of a pressing in operation unless it is positively guided by appropriate dies and means the pintle will tip in some direction of the space with respect to the axis of the housing bore and before it would gain 15 sufficient self guidance in the bore, the bore will be spoilt unless as above mentioned very accurate and expensive guide means are provided. Due to the fact that the pintle is necessarily hardened and the casing is usually of nickel cast iron 20 which is substantially softer material than the hardened nitr alloy pintle, it is obvious that a very hard pintle shank having a larger diameter than the bore in which we intend to press it in, it will act as a broaching tool and will enlarge 25 the bore instead of stretching it for the purpose of an adequate press fit connection. It will be noted further on that it is imperative to seal the ports 5 and 6 against leakage during pressure periods of the reversible ports as well 30 as against air suction during suction periods. In order to solve all the coordinated problems of a sound hydraulic connection at this point I provide a shrink fit connection by either reducing the diameter of the shank portion 1 of the pintle 35 or by expanding the bore of the associated hub 38c by heat subtraction or by heating the same respectively.

The first method comprises the application of such cooling means as dry ice, or the equivalent, 40 which can be easily arranged in an isolated pot of such dimensions which will allow the introduction of the pintle for a certain length of time to lower its temperature below the shop temperature. It is required a shrinkage equivalent 45 to several thousandths of an inch for the shrink fit. The method thus will comprise of keeping the casing of body 38 on shop temperature, the pintle in a refrigerator, dropping the pintle into its coacting bore in the right position and keeping 50 it there undisturbed until the pintle will assume the shop temperature. It will then be noted that the high-finished bore of the body 38 will receive and grip the highly ground and polished pintle shank 1 into a smaller hole without tipping or cutting which would occur by pressing- 55 in operation.

The cylinder barrel 13 is mounted at both ends in the casing on antifriction means 24 and 25 respectively. The antifriction means 24 and 25 60 comprise combination radial load and axial thrust complete bearing assemblies, including inner races 22 and 23 and outer races 26 and 27 respectively. It will be seen that due to the accurate alignment of the pintle in the casing it 65 will be relatively easy to obtain concentricity between the bore of the barrel and the shrink fitted pintle. The cylindrical portion of the casing preferably is made integral with the pintle supporting end of the housing. Thus there is all 70 necessary requirements provided for accurate machining as well as assembly of the various portions of the casing in order to obtain coaxial relationship between bearing means 24 and 25 and casing thereby between the rigid pintle and 75 the coacting barrel 13.

The barrel is provided with supporting flange 14 at the supported portion of the pintle whereas at the opposite end it is provided with an extension portion as at 15 in order to rigidly secure an impeller shaft 11 thereto. Preferably 5 at this end the barrel is provided with a tapered hole or bore 8, coaxial with the pintle to receive a conical portion as at 7 of impeller shaft 11. A splined or keyed connection for driving torque transmission is provided as at 9, whereas the 10 axially rigid relationship between the impeller 11 and the engaging portion of the barrel 15 is further assured by lock nut 12. For this end the impeller shaft is threaded as at 10 to receive the threaded nut 12. The nut may be further 15 secured against rotation or movement with respect to the coacting abutment of the barrel by appropriate axial set screw not shown in the drawings. It will be noted that a rigid and sealed connection between the impeller connection 7 and the associated barrel end 15 will be necessary in order to prevent the escape of the 20 slip fluid from the cylinders, between pintle 2 and coacting barrel and force the slip fluid to work backwards toward the opposite end of the 25 pintle and barrel, and thereby cut the amount of effective slip to one half of the normal conventional slip.

In order to sustain the thrust forces imposed upon the adjacent ends of the pintle 2 and impelling means 7, it is necessary for the bearing means 25 to have sufficient thrust capacity outside of its radial load capacity.

The cylinder barrel 13 is further provided with a plurality of radial cylinders as at 18. Each cylinder 18 is provided with a radial port 17 for the purpose of communication between the cylinder and the coacting ports 3 and 4 of the pintle 2 during rotation. Each cylinder 18 is provided with a radial piston 19. This piston 19 has further provisions, as hereinafter will be seen in order to associate with an enlarged piston actuating head 20. Piston actuating head 20 is primarily guided in an appropriate radial flange as at 16 in order to provide rolling frictional driving relationship between the barrel 13 and an associated 45 rotary assembly comprising a cylindrical ring support as at 32 and associated secondary support rings as at 29-29.

The piston proper 19 is provided with a spherical thrust head as at 19b in order to engage concentrically a coacting straight faced bottom 20b of the head 20. It will be seen that a radial bore provided in the head 20 which has slightly greater diameter than the piston itself, has a flat bottom as at 20b so that at all times the 55 hydraulic piston load will be transmitted to said bottom thrust face 20b in the way of a concentric load transmission of the one point contact concentrated load type. Due to the surrounding clearance space provided around the neck 19a of the piston and between the radial connection hole of the head 20, piston 19 will be able to cooperate with its cylinder 18 in such a manner that a continuous, and hydrostatically balanced pressure oil film will be provided in the small capillary working clearance space between piston 19 and cylinder bore 18 in such a manner that no friction or wear will take place due to the lack of misalignment or excessive transverse 65 pressure therebetween. Thus it will be noted that in case of large power units where each piston and cylinder have to develop considerable horsepower, such provisions for efficient cooperation are important.

The piston drive head 20 is further provided with a circular groove in such a manner that in the plane of cross section Fig. 2, this groove will cooperate with the neck portion 19a of the piston 19 in order to receive a spring member as at 21, in order to actuate the piston 19 during suction stroke. It will be seen that the neck portion of the piston 19a has such diameter that the spring member 21 may be pressed in entirely into the groove of said neck portion so that the outside diameter of the spring 21 will be equal or less to the bore diameter of the receiving hole of head 20. In this manner by compressing the spring 21 snugly about the neck portion 19a of the piston 19 it will be possible to introduce the piston into the coacting hole of the head. Upon relieving the spring it will automatically expand and press against the circular groove of the head 20 in such a manner that sufficient projection is left 20 in order to engage the shoulder of the neck groove 19a. In this manner a floating connection will be provided between a large driving head 20 and the piston 19. The flange 16 of the cylinder barrel 13 will engage the working side walls 20a of the heads, for guiding and torque transmission. The guiding will take up the transverse forces resulting from the nature of the load transmission between a cylindrical support 32 and a coacting radial thrust head 20 and its associated 25 means.

The radial thrust head 20 is further provided with a cylindrical bore as at 20d in such a manner that the thrust pin which is received in this thrust bore will be mounted on its thrust transmitting side or projection on anti-friction rolling elements 28. For this purpose an enlarged and concentric cylindrical surface as at 20c is provided for the rollers 20. The thrust surface 20c will be thus concentric with the bore 20d. It will be noted that for the operation of head 20 during the suction period the thrust roller 31 will engage the remaining portion of bore 20d, after the provision of enlarged concentric bore 20c.

Large thrust rollers as at 31 are provided for 45 thrust loads between the driving heads 20 and the rotating floating support 32 as shown in Fig. 1. It will be noted that the thrust rollers 31 are engaged throughout the entire lengths of the roller with the support for rolling reciprocation and for primary load transmission therebetween. Each pin 31 is further provided with secondary reduced portions as at 31a for the purpose hereinafter to be described. The unitary floating support 32 is provided with slight radial shoulders 50 as at 32a in order to receive secondary supports 29-29 respectively. Each of the secondary supports 29 is rigidly secured at the respective ends of the main support 32 by appropriate means such as press fit or the like. A slight radial shoulder of the secondary support 29 as at 29a will be pressed against the coacting radial shoulder 32a of the main support 32.

Each secondary support 29 is further provided with normally aligned continuous circular grooves as at 30 in such a manner that the reduced ends 31a of thrust pins or rollers 31 will be received therein. The assembly of the pin 31 will be such that for the primary thrust load 31 will be always positively supported by the main support 32 outwardly and will not be hindered in this respect by the reduced ends 31a. Furthermore the reduced ends 31a for the secondary pins will be assembled in the groove ways 30-30 in such a manner that a positive contact between the pin ends and the working sides of the groove during

suction stroke will have positive contact and coaction with the rings 29. Thus simultaneously, the large portion 31 of the thrust pin will be in positive thrust engagement with the inner surface of the main support 32, whereas the pin ends 31a will have positive engagement with the inner working surfaces of the thrust grooves 30-30. The outer faces of the thrust grooves 30-30 thus will have slight operating clearance for the pin ends to allow both positive coaction between the primary and secondary supports and the primary and secondary thrust means respectively.

The main support 32 is formed with slight circumferential recess to the extent of the entire lengths of rollers 34. Cage member 33 will engage the rollers for frictionless rolling cooperation. A stationary support as at 36 will engage the rollers 34 in such a manner that the main support 32, the interposed rollers 34, and the stationary member 36, will form in assembly an efficient complete bearing assembly. The complete bearing assembly will be provided with stroke adjusting and guide means as at 35 and 37 in order to change the stroke of the piston and the delivery of the pump.

The stationary support 36 is provided with conventional parallel guiding and supporting bearing surfaces in coaction with the pump housing not shown in the figures. During stroke adjustment the entire piston actuating assembly including a rotary and stationary support will be shifted parallel with itself to various positions of eccentricity in order to impart variable stroke and variable delivery to the pump. It will be noted that it is important that during the shifting operation a strictly translatory motion be performed on the reactance assembly in order to keep the axis of the thrust rollers 31 parallel with the moving axis of the reactance as well as with the stationary axis of pintle and cylinder barrel. If the axis of the reactance during shifting operation remains not parallel with the axis of the pintle and barrel it is obvious that the driving head 20 will not function properly and undue transverse forces and wear will be imposed on the driving heads and their associated guide ways, which are primarily directed by the coacting flange 16 and its axis of rotation which is coincident with the axis of pintle and barrel respectively.

Various changes may be made in the embodiment of the pump hereinabove specifically described without departing from or sacrificing the advantages of the invention, as defined in the appended claims.

I claim:

1. In a rotary radial piston pump or motor, a rotatable barrel, a radial flange on the barrel, radial cylinders in the barrel in the zone of the flange, radial guideways in the flange respective to the cylinders, a valve pintle in valving cooperation with the cylinders, pistons in the cylinders respectively, a rotary reactance surrounding the cylinders and pistons, and means operatively connecting the rotary reactance to the pistons for actuation of the pistons upon concurrent rotation of the barrel and reactance rotor, said means comprising heads for the pistons respectively reciprocable in said radial guideways, each of said heads having a transverse circular wall groove extending parallel to the axis of rotation of the barrel and open toward the rotary reactance, rolling elements having their axes of rotation substantially parallel with the axis of rotation of the barrel and accommodated in the

- grooves respectively, each element having a central load transmission portion of its peripheral surface in direct rolling load transmitting contact with said reactance and a diametrically aligned opposite load transmitting peripheral surface portion and having two adjacent secondary portions positioned circumferentially between the first portions and engaged by portions of the wall of the associated groove for actuating the pistons during the suction stroke, an arcuate recess in the base of each groove and terminating intermediate the circumferential limits of the groove, and free anti-friction rollers in each recess between said diametrically aligned opposite load transmitting peripheral surface portion of the rolling element and the bottom of the recess for effecting anti-friction load transmission between the said rolling element and the associated piston head, and anti-friction means supporting said rotary reactance directly in the zone of the said rolling elements.
2. In a rotary radial piston pump or motor, a rotatable barrel, a radial flange on the barrel, radial cylinders in the barrel in the zone of the flange, radial guideways in the flange respective to the cylinders, a valve pintle in valving cooperation with the cylinders, pistons in the cylinders respectively, a reactance surrounding the cylinders and pistons, and means operatively connecting the reactance to the pistons for actu-

ation of the pistons upon relative rotation of the barrel and reactance, said means comprising heads for the pistons, respectively reciprocable in said radial guideways, each of said heads having a transverse arcuate groove extending transversely of the associated head and open toward the reactance, cylindrical rolling elements rotatable in said grooves respectively and having their axes of rotation substantially parallel with the axis of rotation of the barrel, each element having a portion of its peripheral surface in direct rolling contact with said reactance at the open portion of the groove and a diametrically aligned opposite load transmitting peripheral surface portion, and having two adjacent secondary portions positioned circumferentially between the first portions and engaged by the portions of the wall of the associated groove for actuating the associated piston during the suction stroke, an arcuate recess in the base of each groove and terminating intermediate the circumferential limits of the groove, and free anti-friction rollers in each recess between said diametrically aligned opposite load transmitting peripheral surface portion of the rolling element and the bottom of the recess for effecting anti-friction load transmission between the said rolling element and the associated piston head.

ELEK K. BENEDEK. 30
